UNITED STATES PATENT OFFICE.

HYLA F. MAYNES, OF NORTH TONAWANDA, NEW YORK, ASSIGNOR TO MAYNES CORPORATION, OF DOVER, DELAWARE, A CORPORATION OF DELAWARE.

DRIVE FOR AMUSEMENT RIDES.

Application filed July 18, 1925. Serial No. 44,589.

This invention relates to amusement rides and in particular to a novel drive for a round-about or other rotary ride. In my Patent No. 1,501,613 I have illustrated and 5 described a rotary amusement ride comprising a series of horizontal radial sweeps rotatable about a central fixed axis and supported at their outer ends by means of wheels journalled on the sweeps which run upon a 10 circular and undulating trackway. The inner ends of these radial sweeps are pivotally mounted upon a rotatable hub or spider to permit of swinging in a vertical plane as the ride follows the undulations, and their outer 15 ends are connected by means of pivoted links which hold the sweeps in spaced relation. Mounted upon these links are passenger-carrying cars. The ride is rotated by means 20 of a cable which encircles the ride and makes contact therewith through a series of cable guide blocks secured to the lower sides of the sweeps. It is the object of the present invention to devise an improved drive for rides of this general character.

25 In accordance with the present invention I mount upon certain of the sweeps, near their outer ends, electric motors which, through the necessary transmission gearing, drive the supporting wheels of the sweeps 30 which are journalled coaxially thereon. These motors, when fixed directly to the sweeps, exert a continuous torque of considerable magnitude upon them and place a strain on the pivot pins at the inner ends 35 of the sweeps. It is possible so to construct the ride that this strain has no serious consequence. I prefer, however, to mount the motors loosely relative to the sweeps and secure them to one of the connecting links 40 to take the torsional strain. Thus no torsional strain is placed upon the sweeps themselves and as the sweeps move up and down along the undulations the motors are free to oscillate slightly about their supports.

45 In the accompanying drawings I have illustrated a preferred embodiment of my invention. In these drawings Figure 1 is a fragmentary plan view of a rotary ride equipped with a drive of the present invention; Figure 2 is an enlarged vertical radial section taken through the ride; Figure 3 is a detail showing a method of mounting the motors and the supporting wheels on the ends of the sweeps, and Figure 4 is an elevation taken along line 4-4 of Figure 2

showing a section of the undulating trackway and the manner in which motors are secured to the links or spacing elements.

The merry-go-round ride shown in these drawings comprises a central stand pipe 1 fixedly mounted upon a suitable base or standard 2 and acting as a pivot or axis for the ride. Upon this stand pipe is fixed a thrust bearing 3 upon which rotates a sweep-spider 4 to which are pivotally connected 60 for swinging movement in a vertical plane a series of radial sweeps 5. Pivoted to the outer ends of these sweeps is a train of cars 6, each car being supported upon two links or spacing elements 7 between two sweeps as 65 clearly shown. At the outer end of each sweep is mounted a wheel 8 running upon an undulating trackway 9, these wheels supporting the weight of the cars. As illustrated in Figure 3 each of these wheels 8 is 70 journalled upon a bearing on the end of a spindle 10 which extends within the hollow outer end of a sweep and is secured in position by means of pins 11. Beyond this 75 trackway is situated a loading platform 12 which follows the undulations on the trackway and encircles the ride. Both trackway and platform are supported upon suitable standards 13 and held in place relative to the central stand pipe by means of tie 80 rods 14.

I shall now describe the novel drive of the present invention. Near the outer end of each third sweep a sleeve 15 is loosely journalled and on this sleeve is mounted an electric motor 16. The motor is held in upright position by means of a rigid bar 17 extending from the motor to one of the adjacent links 7. Power is transmitted by means of a pinion 18 fixed upon the outer end of the 90 motor spindle and meshing with an internal gear 19 fixed to the inner face of the wheel 8. The current for the motor is supplied through leads 20 which extend along the sweep and make contact with collector rings 100 21 concentric with the stand pipe 1 which collector rings in turn receive current through spring-pressed brushes 22. The current to the ride is controlled by the operator by means of an outside switch not 105 shown.

The ride illustrated operates as follows: The passengers having been seated within the cars the current is thrown on and the driving wheels 8 rotated by means of the 110

motors 16. The tendency of the motors to swing due to the driving resistance of the ride, particularly when starting from rest, is counteracted by the bars 17 which transmit the push or pull directly to the links 7. The sweeps are then freed of any torsional strain. As the ride passes over the undulations and the sweeps rise and fall, each motor, held in rigid connection with a link 7 oscillates slightly about its sweep.

I claim:

1. An amusement ride comprising the combination of a central pivot, a plurality of radial sweeps designed to rotate about the pivot, wheels on the sweeps, a circular trackway upon which the wheels run, links between the sweeps and pivotally connected

thereto, a driving motor carried by a sweep but loosely connected thereto and a rigid connection between the motor and a link.

20

2. An amusement ride comprising the combination of a central pivot, a plurality of radial sweeps designed to rotate about the pivot, supporting wheels on the sweeps, a circular undulating trackway upon which the wheels run, links between the sweeps and pivotally connected thereto, a driving motor pivotally mounted on a sweep, transmission gearing between the motor and the supporting wheel, and means connecting the motor with a link for taking up the torsional driving strain.

25

In testimony whereof I affix my signature.

HYLA F. MAYNES.
